UNITED STATES PATENT OFFICE.

WILLIAM CHURCHILL, OF CORNING, NEW YORK, ASSIGNOR TO CORNING GLASS WORKS.
A CORPORATION OF NEW YORK.

REFRACTING COVER-GLASS FOR AUTOMOBILE-HEADLIGHTS.

1,283,671.

Specification of Letters Patent.

Patented Nov. 5, 1918.

Application filed October 3, 1917. Serial No. 194,516.

To all whom it may concern:

Be it known that I, WILLIAM CHURCHILL, a citizen of the United States of America, and a resident of Corning, N. Y., have invented certain new and useful Improvements in Refracting Cover-Glasses for Automobile-Headlights, of which the following is a specification.

The automobile headlight now in common use comprises a light source, a reflector and a cover glass, the arrangement of the parts being such that the mirror reflects light issuing from its focal point in an approximately parallel beam. Inasmuch as commercial light sources are not point sources, there exists a certain amount of dispersion of the beams projected by the projectors. This is objectionable, in that the rays reflected by the mirror upwardly and forwardly from the principal axis of the mirror are thrown into the eyes of the approaching driver with the effect of blinding him, so that legislation has been enacted in many of the States requiring that none of the rays from the reflector shall rise above a plane parallel with the ground level on which the car is moving. It has been proposed for the purpose of avoiding this upward projection of certain reflected rays above the principal axis of the headlight to press on the cover glass a series of prisms so proportioned that they will cause a downward deflection of the rays passing therethrough equal to the angle formed between the upwardly projecting rays falling thereon and the principal axis of the headlight.

If rays projected by the reflector of a headlight from any practicable source be analyzed, it will be found that each part of the reflector is the source of reflected rays issuing therefrom in a cone, the angle of which is the same as the angle at such point of the reflector subtended by the corresponding dimension of the source. Thus the amount of vertical divergence of the rays projected from any part of a reflector will vary with the shape of the light source. If the source be spherical, it will be found that the maximum vertical divergence will be from points on the reflector located at a slight distance from its intersection by the principal axis such points being located in a circle, and the divergence decreasing at points inside and outside such zone. If on the other hand, the source of light be not in the form of a

sphere, the points on the reflector producing equal vertical spread are no longer arranged in circular zones. If the light source has a considerable axial length in respect to its breadth, points of maximum vertical spread are created near the top and bottom of the reflector without a corresponding increase of vertical spread on corresponding points on the horizontal axis of the reflector. Thus points of equal spread with such a light source are no longer arranged in a circular path, but are arranged in elliptical paths, the major axes of which are vertical. In either case, points located in horizontal zones across the reflector are not seats of equal vertical spread of rays, and hence a horizontal prism of uniform base angle, is formed at one point to properly correct the divergence of the reflected rays passing therethrough, will not properly correct vertical spread of reflected rays passing through it at other points of its length. This has been recognized and attempts have been made to meet it, either by giving to the prism throughout its length a corrective value equal to the desired corrected value for the reflected rays of maximum divergence falling thereon at any point (in which case an over-correction is made as to other points), or else the surface of the prisms have been warped so that each prism has a base angle different at different points of its length, in accordance with the desired corrections to be made at the several points. This latter is inconvenient as a manufacturing problem, and it is the purpose of this invention to so construct refractive prisms that with a fixed angle, they will have a proper corrective value at each point for the rays passing through such point.

As will be noted from what is said above, the proper vertical corrective value for points on the cover glass located in the same horizontal plane will increase with practical light sources from the outer margins of the circle of the headlight toward the center thereof. If the reflector (or cover glass therefor) be divided into a plurality of horizontal zones, it will, therefore, be noted that the point of maximum vertical divergence of each zone is at or near the center thereof, with points of minimum vertical divergence at the outer ends.

I propose to take advantage of this fact to obviate the necessity of warping the

prisms by forming one of the refracting faces of each prism on the surface of the frustum of a cone, whose axis is so situated in respect to the optical axis of the headlight 5 that the prism formed thereby passes through points on different horizontal zones of the cover glass. As the downward deflection produced by each point of such a prism varies with the cosine of the angle 10 formed between the radius to such point and the vertical, each prism, while having a uniform base angle throughout, varies throughout its length in power of vertical refraction. By a proper selection of constants 15 such prisms may be caused to pass through such points on the cover glass that the vertical refractive power of the prism at several points on the cover glass will be such as to cause the amount of vertical correction de- 20 sired for such points.

My invention, therefore, consists in a cover glass having such prisms thereon, and it further consists in a cover glass having in addition to such prisms ancillary refracting 25 elements adapted to correct vertical divergence at certain portions of the cover glass, and to cause side-dispersion, as will be hereinafter more fully described.

Referring to the accompanying drawings 30 in which corresponding parts are designated by corresponding marks of reference:—

Figures 1 and 2 are diagrams illustrative of principles made use of in this invention. Figs. 3 and 4 are an elevation and section, 35 respectively, through a cover glass illustrative of my invention.

Figs. 5 and 6 are a rear view and section, respectively, illustrating a cover glass embodying the preferred form of my invention. 40 Considering a curved prism, one of whose faces is formed on the curved surface of the frustum of a cone and another of whose faces is formed by the flat base of the cone, let the face $a-b$, Figs. 1 and 2, be a curved 45 face and the face $a-c$, the flat face, respectively, the axis of the cone by which they are formed being $d-d'$. Then all rays, such as $e-f$, parallel with the axis $d-d'$, fall on the face $a-c$ at a normal thereto and enter 50 the prism without refraction. They however, suffer refraction on passing out of the prism through the face $a-b$ and are bent in the direction $d'-e$ across the axis, the angle $d'-e-f$, measuring the refraction of 55 the rays, being dependent on the angle $c-a-b$ and the index of the refraction of the prisms. As this angle is uniform at all portions of the prism, all rays parallel with the axis $d-d'$ will be bent toward such axis 60 equally. Considering the axis $d-d'$ as horizontal, the ray $e-f$ striking the prism vertically above such axis is deflected downwardly in the vertical plane toward the axis $d-d'$ through the same degree that a ray 65 parallel to $d-d'$ striking the prism at the

point e' horizontally to one side of the axis $d-d'$ is deflected sidewise in the horizontal plane of the axis. Rays parallel to the axis $d-d'$ and striking the prism at points between the points e and e' , before referred 70 to, will be directed toward the axis $d-d'$ downwardly and sidewise, in a plane inclined to the vertical and in which the point e^2 and the axis $d-d'$ are located. The vertical component of this deflection will have as 75 a factor the cosine of the solid angle between the planes e^2-d-d' and $e-d-d'$, that is to say, the cosine of the angle $e-d-e^2$ (Fig. 2) between the vertical and the radius to the circle formed by the prism 80 at the point e^2 . Thus a circular prism of uniform angle possesses for rays axial to the cone of which it forms a part of the base vertical refractive power at different points around its circle. In a like manner 85 the horizontal refractive power of such a prism varies with the sine of the angle $e-d-e^2$.

I propose to take advantage of these properties of such a prism to obtain the desired 90 amount of vertical dispersion at different points on the cover glass, by causing a prism of selected corrective value at its upper portion to pass through such other points on the cover glass that the vertical corrective 95 power of such points of the prism will be such as to cause the vertical correction for reflected rays desired at such points. Inasmuch as with a focused light source of dimensions actually in use every part of a 100 cover glass demands refractive vertical correction to some extent, it is impracticable to use the lower half of the solid conical frustum for which the upper part is used, for such lower half will produce upward refraction if the axis of the cone be parallel with the principal axis of the headlight, or to use any but a part of the upper half of the frustum, as the portions thereof located at the ends of the horizontal radii possess, as 110 above pointed out, no downward refraction. For this reason I prefer to use only the portions of the frustum located at an appreciable angular distance above the axis thereof, so that all portions of each prism will have 115 a vertical component of refraction.

Referring to Fig. 3, let it be presumed that the cover glass 1 shown therein should, for the purposes had in view and when used in connection with a given reflector and a focused light source, provide for downwardly bending rays passing therethrough at the several points noted thereon of the degrees indicated at such points, which amounts will be hereinafter called the 120 desired correction. It will be noted that this figure gives values, for purposes of illustration, of two points vertically over the center of the cover glass, this latter being the point at which the principal axis of the 125

headlight passes therethrough. One of these points (*m*) calls for 4 degrees of correction, and I accordingly place on the cover glass at such point a curved prism 2^a the angle 5 between the front and rear face of which measured on its radius will provide for the correction of the amount called for. The point *n* located to one side of the vertical medial line and at a lower level than the 10 point *m* has a desired correction less than that of the point *m*, namely, a correction of 3 degrees. To obtain this correction by the same prism (2^a) that provides for the correction at the point *m*, such prism is formed 15 by a part of a frustum of a cone, the base radius of which is so selected that the curved prism formed thereby will cover the point *n* and the axis of which, while parallel with the principal axis of the headlight, will be 20 so situated that it will pass through the cover glass at the point *o* so selected that the angle $m-o-n$ made by the radii from such axis to the points *m* and *n* is of such value that the cosine of the angle $m-o-n$ 25 multiplied by the corrective value of the prism at *m* will be substantially equal to the correction desired at *n*.

Inasmuch as, generally speaking, the point of smaller desired corrective value (*n*) 30 will be nearer the horizontal diameter of the cover glass than the point of larger corrective value of the same prism, this means that the axis of the frustum will be decentered from the center *h* of the glass and 35 the principal axis of the headlight, and will be below and parallel thereto. The point *p* is also on the vertical diameter and requires a greater correction than *m*, and therefore I place on the cover glass at such point a second prism 2^a giving at the point *p* the desired correction. This prism, in view of the greater correction required at point *p* will 40 be formed by a frustum whose base angle is greater than that forming the face of the prism 2^a , and the principal axis thereof will be so located that it will, under the rule, provide, as above stated, the desired 45 correction at the point *q*. Obviously the axes of the two frusta may or may not coincide. In the first the prisms will be concentric, which is convenient in manufacture, and to accomplish this a latitude in 50 ratio of the correction obtained to the correction required, may be allowed. In Fig. 55 3 I have shown the axes of the two frusta non-coincident, the axis of the frustum forming prism 2^a intersecting the plate at the point *o'*.

Obviously the several partial frusta may 60 be superimposed the one upon the other, as is illustrated in Fig. 4. This results in an objectionable thickness of the cover glass, and hence I prefer to form the prisms into a series of steps, that is, to form each prism 65 by a part of that portion of the frustum

which remains after removing therefrom a cylinder of the same height whose diameter is the same as the smaller diameter of the frustum.

The application of these principles to a 70 cover glass is shown in Figs. 5 and 6. Here the cover glass has formed on one face thereof a series of concentric prisms 2^a , 2^b , etc., such prisms being of the character before described and being curved 75 around a common axis *o* located below and some distance from the center *h* of the glass, each prism being of uniform angle throughout its length, but the several prisms varying between themselves in angle, in accordance with the principles already stated. The distance *h-o* is such that the several prisms strike the annular shoulder 3 formed near the edge of the glass above the level 80 of the axis *o* so that all portions of each prism have a downward component of refraction, while certain portions of the several prisms have also a side-component of refraction, which is desirable in providing for the horizontal spread of the beam. 85

The prisms are by preference formed only on the rear and inner faces of the cover glass, in order to leave a smooth face to prevent the lodgment of dirt. Obviously my invention is not restricted in this respect. 90

It may under certain circumstances be desirable to place on the cover glass refracting elements other than the circular prisms, in order to provide for greater side spread than is given by such prisms, or for other 100 reasons. Such elements are shown in Fig. 5 in which as the common center of curvature *o* is located at a distance below the principal axis of the headlight less than the radius of the face of the cover glass, a line 105 is formed between the ring 3 and the inner prism 2^a at the bottom part of the cover glass on which there are no circular prisms. This space may be formed in any desired means with a view of preventing glare or 110 of obtaining side spread, and for this purpose I may use, as shown in the drawings, angular 4 such, for instance, as shown in the application of Gage and Pascucci, filed in the United States Patent Office on the 115 12th day of December, 1916, serially numbered 136,437.

Inasmuch as there is a tendency of the prisms to suck up in the molds, especially near the ends thereof, I prefer to place on 120 such prisms strengthening ribs 5 extending radially thereof and acting, due to the fact that they quickly chill, to prevent distortion in raising the plunger.

Having thus described my invention, what 125 I claim and desire to secure by Letters Patent is:—

1. A refracting cover glass for automobile headlamps, having thereon a series of prisms, one of the refracting faces of each 130

prism being on the surface of a conical frustum whose axis is so placed and whose base is such that the several prisms at different points throughout their length have vertical refractive power substantially equal to the vertical refractive power necessary at such points of the cover glass to overcome the upward divergence of rays from the headlight reflector falling on the cover glass at such points.

2. A refracting cover glass for automobile headlights, having thereon a series of prisms, one of the refracting faces of each prism being on the surface of a conical frustum whose axis intersects the plane of the glass away from the center thereof at such a distance that the several prisms at different points throughout their lengths have vertical refractive power substantially equal to the vertical refractive power necessary at such points of the cover glass to overcome the upward divergence of rays from the headlight reflector falling on the cover glass at such points.

25. 3. A refracting cover glass for automobile headlights, having thereon a series of prisms, one of the refracting faces of each prism being on the surface of a conical frustum whose axis is parallel with the axis of the headlight and is at such a distance therefrom that the several prisms at different points throughout their length have ver-

tical refractive power substantially equal to the vertical refractive power necessary at such points of the cover glass to overcome 35 the upward divergence of rays from the headlight reflector falling on the cover glass at such points.

4. A cover for automobile headlights having thereon above the optical axis a series 40 of curved refracting prisms, and below the optical axis a series of horizontal prisms, the center of the curvature of the curved prisms being below the optical axis of the headlight.

5. A cover for automobile headlights having thereon a series of curved refracting prisms, each prism being formed by not more than the upper half of a conical frustum whose axis is located below the 50 optical axis of the headlight, and also having a series of downwardly deflecting prisms located between the ends of the inner of such curved prisms.

6. A refracting cover glass for automobile headlights, having thereon a series of prisms, certain of the prisms having thin transverse flanges projecting therefrom and serving by their quick cooling to prevent 55 sucking up of such prisms in molding.

In testimony whereof I have signed my name this 27th day of September, 1917.

WILLIAM CHURCHILL.
